PROCESS FOR SOLVENT EXTRACTION OF
OIL

David R. Merrill, Long Beach, Calif., assignor to
Union Oil Company of California, Los Angeles,
Calif., a corporation of California

Application January 19, 1934, Serial No. 707,324

15 Claims. (Cl. 196—13)

This invention relates to the extraction of oils by employing a selective solvent. Although applicable to the treatment of other oils, it refers more particularly to the production of lubricating oil by a selective solvent extraction process.

It has been found that desirable paraffinic hydrocarbons can be separated from the undesirable olefinic, naphthenic and/or aromatic compounds by the use of solvents which selectively dissolve the undesirable hydrocarbons but which exhibit only a very limited solvent power upon the desirable paraffinic hydrocarbons.

When I use the term "paraffinic hydrocarbons" I mean those highly saturated compounds which are present in petroleum and are characterized by low temperature viscosity susceptibility, i. e. they exhibit a minimum change in viscosity for a given change in temperature. They also are characterized by relative stability to air and sunlight, exhibiting little tendency toward discoloration or sludge formation. This definition is not meant to include those compounds which are usually solid or semi-solid at ordinary temperatures and which are known as "wax" or "petrolatum," but, of course, it is obvious that my invention is meant to also include the selective extraction of waxy oils. As a matter of convenience hereafter, I will refer to the undesirable components, such as olefinic, naphthenic and/or aromatic hydrocarbons, as the "non-paraffinic" components of petroleum. These fractions are characterized by a relatively high temperature viscosity susceptibility and are relatively unstable to air and sunlight, exhibiting discoloration and sludge formation.

A number of selective solvents for extraction have been found, for example, it has been shown that such materials as aniline, chloraniline, nitrobenzene, dichlorethyl ether, phenol, chlorophenol, cresol and cresol with a small proportion of water, for instance 4%, are highly selective as solvents for the non-paraffinic hydrocarbons. When these solvents are commingled with petroleum or petroleum fractions under the proper conditions of temperature, the undesirable non-paraffinic hydrocarbons pass into solution to a greater or less extent but a substantial proportion of the desirable paraffinic hydrocarbons remains undissolved. The solution of undesirable hydrocarbons and solvent settles to the bottom of the container and forms an extract phase when relatively heavy solvents are employed. The relatively light paraffinic hydrocarbons rise to the top of the vessel and form a raffinate phase. These phases are then readily separable by or-

dinary decantation means. The raffinate phase is usually found to contain a small quantity of the selective solvent and the extract phase ordinarily contains a relatively large quantity of the solvent. These fractions may be purified by distillation whereby the solvent is distilled away from the hydrocarbon oils.

I have found that in the usual solvent extraction of mineral oil with the above mentioned selective solvents, the separation is not complete. Particularly, all of the paraffinic hydrocarbons, i. e. the more valuable lubricants, are not obtained in the raffinate phase but instead some of the oil fractions which are preferred in the raffinate are found in the extract phase. Conversely, some fractions desired in the extract phase are found associated with the raffinate after usual extraction.

It has been known in the solvent extraction art that after making a primary separation of raffinate from extract, additional fractions can be made to separate from the extract phase by one or more reductions of temperature which correspondingly reduce the solubility of these oils of relatively high paraffinicity in the extract phase. These oils then form intermediate raffinates which can be separately recovered by decantation from the remaining extract phase.

I have discovered that if a material which I term an anti-solvent is added to an extract phase produced by extraction with a selective solvent, the extract phase can itself be separated into a further extract and raffinate of lower and higher quality, respectively than the original extract phase. Also if an anti-solvent is present during at least one of the extraction stages, those fractions desired in the raffinate will be forced into this phase by action of this material without necessarily refrigerating the oil subjected to extraction to the degree heretofore found necessary to render substantially all of those fractions desired in the raffinate insoluble in the extract phase. In fact, in some cases the reduction of temperature may be entirely omitted in my process. In a solvent extraction process of this character, the expense of refrigeration is a substantial item in the cost of operation. My process lowers this cost.

An anti-solvent may be defined as a material which tends to prevent the solution of a hydrocarbon fraction which, except for the presence of the anti-solvent, would be dissolved in the extract phase upon extraction of the oil with a selective solvent. I have found that a number of substances are suitable for use as an anti-

solvent; for instance, liquid normally gaseous hydrocarbons such as liquid ethane, propane or butane, or methyl, ethyl or isopropyl alcohols, methyl cellosolve (mono-methyl ether of ethylene glycol), carbitol (mono ethyl ether of diethylene glycol) and other oxygenated compounds such as acetone or methyl acetate. Even water may be used as an anti-solvent when the selective solvent with which it is employed is at least partly soluble therein. One or more of these anti-solvents may be employed.

Extraction of the oil may be accomplished by a selective solvent modified or unmodified, as desired, by the presence of an anti-solvent and to the extract phase thus produced is added sufficient anti-solvent to cause phase separation of this extract phase. My invention also includes primarily extracting an oil with a selective solvent to produce a raffinate phase and an extract phase and further extracting this extract phase with a selective solvent in the presence of an anti-solvent. If desired, the primary extraction can be in the presence of an anti-solvent and the extraction of the extract phase can be with a selective solvent to which further quantities of anti-solvent are added.

I have also found that in the usual selective solvent extraction of mineral oil, some of the fractions desired in the extract phase are found associated with the raffinate. In order to obtain a high quality raffinate, it is necessary that these fractions be removed. I have discovered that this may be accomplished by extracting the oil in stages in which the solvent power of the selective solvent employed is increased in each successive stage. A final raffinate is thereby obtained which is substantially free of fractions desired in the extract phase. This may be accomplished by first extracting the oil with a selective solvent in the presence of a relatively large amount of anti-solvent and then extracting the raffinate from this extraction with a selective solvent associated with less or no anti-solvent.

It is an object of my invention to extract oil with a solvent in the presence of an anti-solvent to force into the raffinate phase that portion desired in the raffinate which would otherwise remain in the extract phase.

It is a further object to extract an oil with a selective solvent, separate the raffinate from the extract thereby obtained and intermix said extract with an anti-solvent to separate an intermediate raffinate from said extract.

It is another object of my invention to obtain the desired material in the raffinate phase without refrigerating to the temperatures heretofore found necessary for relatively complete separation of paraffinic and non-paraffinic hydrocarbons into raffinate and extract phases, respectively.

A further object of my invention is to produce by extraction with a selective solvent a raffinate substantially free of material desired in the extract phase.

In the drawing:

Fig. 1 is a schematic arrangement of one form of apparatus which may be employed to carry out my process. Fig. 2 is another form of apparatus which I may employ.

Referring more particularly to Fig. 1, extractors 10 and 11 are provided. Oil to be subjected to extraction is fed by action of pump 15 into extractor 10 through line 13 controlled by valve 14. Solvent is introduced into extractor 10 by action of pump 16 in line 17 controlled by valve

18. Raffinate is removed from extractor 10 through line 20 controlled by valve 21. Extract phase from 10 passes through line 22 controlled by valve 23 into coil 24 in cooler 25. As previously stated, the extraction in the first stage, i. e. in extractor 10 does not separate all of the material desired in the raffinate. Some of the material preferred in the raffinate remains dissolved in the extract phase. Accordingly, after the separation in extractor 10 into raffinate and extract phases, it is further necessary to separate an intermediate raffinate from the extract phase passing from coil 24 via line 27.

In order to obtain this intermediate raffinate, an anti-solvent is passed into line 27 by action of pump 30 from line 31 controlled by valve 29. The extract phase and anti-solvent are then passed into an agitator such as orifice mixer 32 where these materials are thoroughly contacted. The mixture is then passed into extractor 11 through line 33 and flows countercurrently to selective solvent entering through line 34 controlled by valve 35 by action of pump 36. Raffinate phase is removed from 11 through line 37 controlled by valve 38. Extract phase exits from 11 through line 40 controlled by valve 41.

In view of the foregoing it is obvious that the oil in extractor 10 is separated into an extract and a raffinate. As previously stated, this separation is not complete because some of the fractions associated with the extract are desired in the raffinate phase. The selective solvent employed for extraction in 10 may be unmixed with anti-solvent or in some instances this primary extraction may take place in the presence of an anti-solvent. In order to obtain thorough extraction and phase separation in extractor 11 it is necessary that the temperature prevailing therein be less than that in extractor 10 when no additional anti-solvent is introduced with the solvent entering via line 34. In fact, the temperature in 11 may be lower in 11 even when anti-solvent is added with the selective solvent through line 34 but sufficient anti-solvent may be introduced therewith so that it does not become necessary to reduce the temperature in 11 below that prevailing in 10. Because the solvent power of the solvent is decreased in extractor 11, an intermediate raffinate is separated therein from the primary extract. The extract passing through line 40 is relatively free of those fractions desired in the raffinate.

In order to remove the solvents and anti-solvents from the extracts and raffinates associated therewith, these materials may be distilled therefrom in the usual manner. It is obvious that in place of the two stage system described a greater number of stages of extraction and anti-solvent addition may be provided.

As an example of the operation of the apparatus disclosed in Fig. 1, petroleum lubricating oil in extractor 10 was extracted with 150 volume percent. of phenol at 125° F. The extract phase was cooled in coil 24 to 90° F. and water was added as an anti-solvent via line 31 in the proportion of 12.5 volume percent. based on the oil originally charged to the system. Extraction took place in 11 by the addition of 50 volume percent. phenol containing 9% water via line 34. It was found that the intermediate raffinate flowing through line 37 contained valuable paraffinic fractions which would otherwise have been lost in the extract flowing from extractor 10 via line 22.

Referring more particularly to Fig. 2, continuous countercurrent extractors 100 and 101 are

provided and oil to be subjected to extraction is fed by action of pump 102 into extractor 100 through line 103 controlled by valve 104. Solvent is introduced into extractor 101 by action of pump 105 in line 106 controlled by valve 107. The final extract phase separated from the raffinate phase is removed from the system by passing from extractor 100 through line 108 controlled by valve 109. Final raffinate phase is removed from extractor 101 via line 110 controlled by valve 111. An intermediate raffinate fraction can be separated and removed via line 133 in a manner to be described.

The oil entering the system through line 103 is subjected to extraction in extractor 100, preferably by passing countercurrently to and in direct contact with a stream of extracting medium to be described entering through line 112. The raffinate from this extraction is removed from 100 through line 113 controlled by valve 114. It passes through coil 115 disposed in heater 116 and then travels through line 117 into extractor 101. Extraction proceeds in 101 by flowing the oil entering via 117 in direct contact with selective solvent entering through line 106.

Intermediate extract phase is removed from extractor 101 through line 120 by pump 121. As previously described, some oil fractions which are desired in the raffinate phase do not remain insoluble in the extract phase and are associated therewith in the stream passing through line 120. Accordingly, after the separation in extractor 101 into final raffinate and intermediate extract phases, it is further necessary to separate an intermediate raffinate from the intermediate extract phase leaving through line 120. By action of pump 121 an anti-solvent may be introduced into line 120 through line 122 controlled by valve 123. The material flowing through line 120 is then brought to the correct temperature by passage through coil 125 in cooler 126. The material from coil 125 flows via line 128 to an agitator such as orifice mixer 130 for thorough agitation and intermixture with the anti-solvent. From this agitator the mixture flows via line 131 into intermediate separator 132 wherein phase separation takes place. The intermediate raffinate phase is removed through line 133 controlled by valve 134. Extract phase from separator 132 freed from intermediate raffinate is removed therefrom by action of pump 135 through line 112 controlled by valve 137 and passes into extractor 100. Thus, the extract phase from separator 132 enters extractor 100 and the solvent associated therewith and modified by the anti-solvent is used as the extracting medium for the oil passing to the extractor 100 via line 103. The extract phase in 112 may be heated or cooled, as necessary, to obtain the desired phase separation in extractor 100.

In view of the foregoing it is obvious that the oil entering extractor 100 is separated therein into an extract and a raffinate by a selective solvent whose solvent power is reduced by the presence of an anti-solvent. As previously stated, this separation is not complete because some of the fractions associated with the raffinate are desired in the extract phase. Consequently, the oil leaving extractor 100 through line 113 is in effect partially extracted oil. The extraction in 100 occurs by direct contact with a mixture of one or more of the above mentioned solvents with one or more of the above mentioned anti-solvents. The partially extracted oil from 100 is further extracted in 101 with solvent preferably unmixed

with an anti-solvent or mixed with a smaller proportion of anti-solvent. Due to the relatively high solvent power of the selective solvent in 101, the raffinate separated therefrom contains little or no fractions desired in the extract phase.

The temperature in extractor 101 may be the same as that prevailing in extractor 100 or the temperature may be increased. In order to free the respective extracts and raffinates from the solvent and anti-solvent associated therewith these materials may be distilled from the extract and raffinate in any usual manner. While I have shown and described a two stage system, in some cases it may be desired to add more extraction stages than here shown and to employ more steps of anti-solvent addition. These modifications will appear obvious to one skilled in the art.

By employing an anti-solvent in the manner described above, extremely low temperatures in extractor 100 otherwise necessary to prevent an excessive amount of extraction at this point are avoided. By avoiding such low temperatures, the process is better adapted for operation on oils of high viscosity or high pour point. The process is also better adapted to operation with solvents of relatively high solidification temperature such as nitrobenzene or phenol.

As an example of the operation of the apparatus disclosed in Fig. 2, petroleum lubricating oil was extracted with 150 volume percent. of phenol entering via line 106. As an anti-solvent there was introduced 15 volume percent, based on the oil feed, of water to the extract phase flowing through line 120. The temperature in extractors 100 and 101 and separator 132 were 90° F., 125° F., and 60° F., respectively. It was found that by this treatment that portion of the raffinate flowing through line 113 which was desired in the extract phase could be removed from the raffinate phase before passage through line 110 from extractor 101. Furthermore, an additional separation into extract and raffinate phases could be accomplished in the presence of the anti-solvent in separator 132.

The viscosity gravity constant, abbreviated V. G. C., is an index of the paraffinic or naphthenic nature of an oil. A high value represents a high degree of naphthenicity while low values indicate relatively greater paraffinicity. This constant is determined by the method employed by Hill and Coates as set forth in the Journal of Industrial and Engineering Chemistry of 1928, volume 20, page 641. When oil of 0.86 V. G. C. was extracted in extractor 100, the extracted oil passing through line 108 had a V. G. C. of 0.96. The raffinate passing through line 113 for extraction in 101 had a V. G. C. of 0.83 and the raffinate passing from the system via line 110 had a V. G. C. of 0.81. The extract in line 120 was characterized by a V. G. C. of 0.88. The intermediate raffinate passing via line 133 had a V. G. C. of 0.86 and the extract returned to extractor 100 through line 112 had a V. G. C. of 0.92. It is thus evident that after removal of the least valuable, highest V. G. C. fractions in extractor 100, a high quality final raffinate was obtained from the stock and from the extract phase produced in extractor 101 there was obtained an intermediate raffinate of better quality than the material flowing through line 120.

In some cases my process may simply comprise extracting an oil with a selective solvent, separating the extract phase from the raffinate phase, adding anti-solvent to the extract phase, cooling the latter mixture if necessary to produce an

intermediate raffinate insoluble in the extract phase by virtue of the addition of the anti-solvent and separately removing from the extraction system the intermediate raffinate and the extract phase freed of this intermediate raffinate. The initial raffinate, intermediate raffinate and extract freed from intermediate raffinate were relatively high, medium and low grade oils, respectively. The solvent and anti-solvent may be removed from the fractions containing the same by any usual means such as by distillation. As an example of this operation, petroleum lubricating oil was extracted with 150 volume percent cresol at 60° F., and the phases were separated. To the extract phase was added 75 volume percent methyl alcohol as an anti-solvent and phase separation into an intermediate raffinate and an extract took place at 60° F. Valuable paraffinic hydrocarbons may thus be recovered from the extract phase.

It will be understood that the foregoing is merely illustrative of certain embodiments of my invention and that many modifications may be made therein without departing from the spirit of my invention.

I claim:

1. A process for the separation of paraffinic and non-paraffinic fractions from mineral oil containing the same which comprises extracting said oil with a selective solvent, separating the extract phase soluble in said solvent from the raffinate phase insoluble therein, commingling said extract phase with an anti-solvent and extracting said mixture of extract phase and anti-solvent with a further addition of selective solvent to separate an intermediate raffinate insoluble in said solvent from the extract phase soluble therein.

2. A process for the separation of paraffinic and non-paraffinic fractions from mineral oil containing the same which comprises extracting said oil with a selective solvent, separating the extract phase soluble in said solvent from the raffinate phase insoluble therein, commingling said extract phase with an anti-solvent and extracting said mixture of extract phase and anti-solvent with a further addition of selective solvent at a temperature lower than the temperature of said first mentioned extraction to separate an intermediate raffinate insoluble in said solvent from the extract phase soluble therein.

3. A process for the separation of paraffinic and non-paraffinic fractions from mineral oil containing the same which comprises extracting said oil with a selective solvent, separating the extract phase soluble in said solvent from the raffinate phase insoluble therein, extracting said extract phase with a further addition of selective solvent in the presence of an anti-solvent to separate an intermediate raffinate insoluble in said solvent from the extract phase soluble therein and removing the solvent and anti-solvent from the separated oil phases.

4. A process for the separation of paraffinic and non-paraffinic fractions from mineral oil containing the same which comprises extracting said oil with a selective solvent, separating the extract phase soluble in said solvent from the raffinate phase insoluble therein, commingling said extract phase with an anti-solvent to separate an intermediate raffinate from said extract phase and extracting oil with selective solvent comprising said extract phase freed from said intermediate raffinate.

5. A process for the separation of paraffinic

and non-paraffinic fractions from mineral oil containing the same which comprises extracting said oil with a selective solvent, separating the extract phase soluble in said solvent from the raffinate phase insoluble therein, further extracting said raffinate phase with selective solvent, separating a final raffinate insoluble in said solvent from intermediate extract phase soluble therein, commingling said intermediate extract phase with anti-solvent, separating an intermediate raffinate from said intermediate extract phase and returning as selective solvent to said first mentioned extraction said intermediate extract phase freed from said intermediate raffinate.

6. A process for the separation of paraffinic and non-paraffinic fractions from mineral oil containing the same which comprises extracting said oil with a selective solvent, separating the extract phase soluble in said solvent from the raffinate phase insoluble therein, further extracting said raffinate with selective solvent at a higher temperature than the temperature of said first mentioned extraction, separating a final raffinate insoluble in said solvent from intermediate extract phase soluble therein, commingling said intermediate extract phase with anti-solvent and cooling the same, separating an intermediate raffinate from said intermediate extract phase and returning as selective solvent to said first mentioned extraction said intermediate extract phase freed from said intermediate raffinate.

7. A method as claimed in claim 4 in which the selective solvent is one of the members selected from the group of aniline, nitrobenzene, dichlor-ethyl ether, phenol and cresol.

8. A method as claimed in claim 4 in which the selective solvent is phenol and the anti-solvent is water.

9. A method as claimed in claim 2 in which the anti-solvent is an alcohol.

10. A process for the separation of paraffinic and non-paraffinic oil fractions from a mineral oil containing the same which comprises commingling said oil with a selective solvent for the non-paraffinic fractions and an anti-solvent adapted to lower the solubility of the paraffinic fractions in the selective solvent which is more soluble in the extract phase than in the raffinate phase and thereby forming a raffinate phase and an extract phase, separating said phases, re-extracting the raffinate with a selective solvent and thereby forming a second raffinate phase and a second extract phase and separating said second formed phases.

11. A process for the separation of mineral oil into fractions relatively more paraffinic in character and relatively less paraffinic in character than the original oil which comprises extracting said oil in a plurality of stages with a selective solvent for non-paraffinic fractions of the oil and with an anti-solvent which is adapted to lower the solvent power of the selective solvent for the more paraffinic oil fractions and which is more soluble in the extract phase than in the raffinate phase, removing a raffinate phase and an extract phase from each extraction stage and progressively diminishing the quantity of anti-solvent as the extraction proceeds from the initial oil feed stage to the stage from which the final raffinate is withdrawn.

12. A process of refining mineral hydrocarbon oils with a solvent refining agent which in its undiluted state is relatively non-selective as

measured by its ability to separate non-paraffinic from paraffinic hydrocarbons and which when diluted with water is relatively highly selective as measured by its ability to dissolve only hydrocarbons of highly non-paraffinic character, comprising treating an oil with the solvent diluted with water, separating the diluted solvent together with its dissolved highly non-paraffinic hydrocarbons from the remaining oil, treating the remaining oil with the undiluted solvent, and separating the undiluted solvent together with its dissolved hydrocarbons from the undissolved oil.

13. Process for separating a petroleum oil into at least three constituents of different characteristics which comprises treating the petroleum oil with a solvent mixture comprising an active solvent substance of the class having a solubility selectivity for aromatic type compounds and an inert solvent material of the class having substantially no solvency for petroleum oil, to obtain a raffinate and an extract of different characteristics, subjecting the raffinate in successive stages to the action of a similar solvent which in each successive stage comprises a greater proportion of the active petroleum solvent and a smaller proportion of the inert material.

14. A solvent refining process for separating a mineral hydrocarbon oil into fractions relatively more paraffinic in character and relatively less paraffinic in character, with a solvent refining

agent which when employed alone is relatively non-selective as measured by its ability to separate non-paraffinic components from paraffinic components of the oil and which when diluted with an anti-solvent is relatively more selective for said non-paraffinic components of the oil, comprising extracting a mineral hydrocarbon oil with said solvent refining agent diluted with an anti-solvent, separating the diluted solvent together with its dissolved components of the oil from the remaining oil, treating the remaining oil with less dilute solvent, and removing an extract phase comprising the less dilute solvent together with its dissolved hydrocarbons.

15. A process of refining mineral hydrocarbon oils with a solvent refining agent which in its undiluted state is relatively non-selective as measured by its ability to separate non-paraffinic from paraffinic hydrocarbons and which when diluted with water is relatively highly selective as measured by its ability to dissolve only hydrocarbons of highly non-paraffinic character, comprising treating an oil with the solvent diluted with water, separating the diluted solvent together with its dissolved highly non-paraffinic hydrocarbons from the remaining oil, treating the remaining oil with less dilute solvent, and removing an extract phase comprising the less dilute solvent together with its dissolved hydrocarbons.

DAVID R. MERRILL.
